UNITED STATES PATENT OFFICE.

WILLIAM H. JAMOUNEAU, OF NEWARK, AND JUSTUS VERSCHUUR, OF JERSEY CITY, NEW JERSEY, ASSIGNORS TO B. F. NORRIS, ALISTER & CO., OF CHICAGO, ILLINOIS.

DESIGN FOR A SPOON.

SPECIFICATION forming part of Design No. 22,499, dated June 6, 1893.

Application filed March 21, 1893. Serial No. 467,081. Term of patent 3½ years.

To all whom it may concern:

Be it known that we, WILLIAM H. JAMOUNEAU, residing at Newark, in the county of Essex, and JUSTUS VERSCHUUR, residing at Jersey City, in the county of Hudson, State of New Jersey, citizens of the United States, have invented and produced a new and original Design for Souvenir Spoons and Similar Flat Ware; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front view of a spoon of our design, and Fig. 2 is a reverse view of the same.

20 The leading feature of our design consists of a souvenir spoon, the front or obverse thereof, and the reverse of the handle, having the ornamentation shown and described.

In said drawings, *a* indicates the handle and *b*, the bowl of the spoon. At the wide upper end of the handle, on the obverse side, the same is decorated with the head of a man, *c*, representing Columbus, which is inclosed in a wreath *d* of laurel and oak. Below this is 25 a shield, *e*, for a legend, inscription, or the like, and below this a symbolic group of ornaments, comprising a globe, *f*, on the face of which is pictured a factory smoke stack, or chimney, *g*, a cog wheel, *h*, and an electric 30 telegraph pole and wires *i*. Below this, toward the shank of the handle is displayed a

mercury wand, *j*, and the shank, *a'*, is decorated with an American flag, *k*, which appears to be spirally wound therearound and over the handle of the wand. An anchor-like decoration, *k'*, appears at the base of the shank between the spiral turns of the flag. The bowl, *b*, of the spoon shows a vessel shaped decoration, *l*, apparently sailing upon the water, *m*, and having, as a back ground, 45 sun rays *n*. The reverse of the handle is decorated with the head, *p*, of a woman with crowned head, representing Queen Isabella, the head being surrounded with a laurel wreath *q*. Below this are crossing flags, *r*, 50 and in the angle formed by the staves is a representation of a rising sun *t*. Below this, in turn, is the representation of a globe, *u*, and, in order, a disk shaped seal *v*. The shank is decorated with a representation of a 55 spirally wrapped flag, *k*, as on the other side.

What we claim as new is—

1. The design for a spoon substantially as herein shown and described.
2. In the design for a spoon, the reverse 60 substantially as shown and described.
3. In the design for a spoon, the obverse substantially as shown and described.

In testimony that we claim the foregoing we have hereunto set our hands this 10th day of 65 March, 1893.

WILLIAM H. JAMOUNEAU.
JUSTUS VERSCHUUR.
